DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

No Drawing. 28 Pages Specification

A class of 5-acyl-2,4-oxazolidinediones of the general formula

in which

X, Y and Z are each defined as oxygen or sulfur;
R¹ represents an aryl, an alkyl, a heterocyclic group,
—NHR and —OR group in which R is defined as hy-
drogen, an aryl, an alkyl, or a heterocyclic radical;
R² is a hydrogen, an aryl group, an alkyl group, or a
heterocyclic group;

said class of compounds having the ability to react with
oxidized color developer to obtain photographically use-
ful yellow dyes; the non-diffusible compounds of this in-
vention being preferably utilized in a color photographic
element as part of one or more light-sensitive silver hal-
ide emulsion layers and the diffusible compounds utilized
by incorporation into a developer composition; also in-
cluded is a process for producing the indicated compounds
by reacting a 2,4 oxazolidinedione or thio analog thereof
with magnesium methyl carbonate, and, thereafter, re-
acting the resulting chelate salt with an acylating agent
or subjecting it to alcoholysis.
